Patented Sept. 1, 1914.

UNITED STATES PATENT OFFICE.

FRANK W. MILLER, OF CHICAGO, ILLINOIS, ASSIGNOR OF ONE-HALF TO CLARENCE D. BAUERS, OF CHICAGO, ILLINOIS.

BOILER WASHING AND FILLING SYSTEM.

1,109,353.

Specification of Letters Patent.

Patented Sept. 1, 1914.

Application filed February 28, 1912. Serial No. 680,386.

To all whom it may concern:

Be it known that I, FRANK W. MILLER, a citizen of the United States, residing at Chicago, in the county of Cook and State 5 of Illinois, have invented certain new and useful Improvements in Boiler Washing and Filling Systems, of which the following is a specification.

This invention relates to boiler washing 10 and filling systems and aims in general to provide a system of this character in which the temperature of the washout water will be maintained by the admixture therewith of the required quantity of blow-off steam 15 and water from a locomotive boiler and in which the refilling water will be primarily heated by exhaust steam in a feed water heater and will be further heated in the filling water reservoir by the introduction thereto of blow-off steam.

Other objects of the invention are, to maintain a uniform temperature of the washout water in the washing water reservoir by maintaining a circulation of the 20 water therein, to maintain the temperature of the filling water in the filling water reservoir by circulating the water from the reservoir through the feed water heater and back to the reservoir, to utilize the 25 surplus steam in the feed water heater by delivering it to the water in the filling water reservoir for heating the same and, to maintain the temperature of both the washout and refilling waters by the admission 30 of live steam when the temperature of the washing water falls below a predetermined point.

Additional objects and advantages of the 35 present invention will be apparent as the invention is better understood by reference to the following description when considered in connection with the accompanying drawings, the single figure of which illustrates in a conventional way one practical 40 embodiment of the invention.

Referring to the drawings, it will be observed that I have provided a large tank 5 divided by a partition 6 into a washing water reservoir 7 and a filling water reservoir 8. It will be obvious, however, as the 50 invention is better understood that the washing water and filling water reservoirs may be made structurally distinct and in-

dependent from each other, if preferred. The blow-off steam and water from the 55 locomotives are discharged through the blow-off main 9 which communicates at its discharge end with a catch-basin 10, of well known or preferred construction, the overflow from this basin being conducted to a 60 sewer or other discharge through the pipe 11. Water from the washing water reservoir 7 is delivered by the pump 12 to the roundhouse through the washout main 13 and refilling water from the filling water 65 reservoir 8 is delivered by the pump 14 to the roundhouse for refilling purposes through the refilling main 15. Adjacent the various stalls of the roundhouse the 70 blow-off, washout and refilling lines are equipped with suitable drops 16 adapted to be connected at their lower ends with a boiler in the usual way. The ends of the washout and refilling lines may be connected to a circulating pipe 17 by means of 75 which circulation may be maintained in these mains.

Cold water is supplied to the washing water reservoir 7 through a cold water pipe 18 connected with any suitable source of 80 water supply and a predetermined level of water is maintained in the reservoir by an automatically controlled float valve 19 adapted to be actuated by a float 21 operating in a float chamber 22 connected with 85 the end of the reservoir. An overflow pipe 23 connecting with the sewer permits escape of surplus water, siphonic action in this pipe being obviated by a small vent pipe 24 communicating with the crown of the 90 pipe 23. The washing water in the reservoir 7 is heated to the required temperature by the admission of blow-off steam and water thereto. To this end I have provided a pipe 25 communicating with the 95 blow-off main 9 and entering the reservoir 7 where it is preferably equipped with a plurality of perforated distributing branches 26 through which blow-off steam and water are distributed and mingled with the wash- 100 ing water. In order to prevent water hammer these branches are preferably equipped with check valves 27.

In certain boiler washing systems designed prior to my present invention provision has been made for admitting cold water 105

to the washing water after it is drawn from the washing water reservoir to reduce the temperature of the washing water sufficiently to enable the washout hose to be handled by the washers-out. My present invention aims to eliminate the tempering down of the washing water by admitting only so much blow-off steam and water to the washing water reservoir as is necessary to raise the washing water to the required washing temperature. I have provided, therefore, in the pipe 25 a thermostatically controlled valve 28 which is controlled from a thermostat 29 disposed within the reservoir 7. When the temperature falls below a predetermined amount the valve 28 will be opened to admit blow-off steam and water until the water in the washing water reservoir has been raised to the required temperature whereupon the valve 28 is automatically closed to prevent further admission of hot blow-off products. To provide for maintaining the temperature of the washing water when locomotives are not being blown off and blow-off steam and water are not available I introduce live steam into the washing water reservoir from a pipe 31 connected with any suitable source of live steam under pressure. A pipe 32 connected with the pipe 31 and provided with the branches 33 within the washing water reservoir conveys the steam into the reservoir wherein it is mingled with the washing water. A thermostatically controlled valve 34 located in the pipe 31 and controlled by a thermostat 35 situated in the washing water reservoir regulates the admission of live steam. Under ordinary conditions the washing water will be heated by blow-off steam and water admitted through the valve 28, but in cases of emergency when blow-off products are not available, as before mentioned, the valve 34 will open thereby admitting live steam to the washing water until the temperature thereof has been raised the required amount. Owing to the tendency of the colder water to seek the lowest level the pump 12 would ordinarily draw from the reservoir 7 through the pump intake pipe 36 the colder water from the reservoir. For the purpose of maintaining a uniform temperature of water throughout the reservoir 7 I have provided a circulating pipe 37 connecting the washout main 13 with the pipe 25 so that water will be constantly withdrawn from the bottom of the reservoir and returned through the perforated branches 26 thereby maintaining a constant circulation and a uniform temperature of the water in the washing water reservoir. A scale pocket 38 is preferably connected with the blow-off main 9 to receive boiler scale, sludge and the like, thereby preventing the same from entering the pipe 25 and clogging the valve 28. Live steam is

supplied to the pumps 12 and 14 through pipes 39 and 41, respectively, in the usual manner.

The filling water reservoir 8 receives its supply of water from the feed water heater 42 which is connected with the reservoir by pipe 43. The feed water heater, as will be observed, is located at the side of the reservoir and near the top and a predetermined level of water in both the heater 42 and the reservoir 8 is maintained by a float 44 operating in a chamber 45 connected with the feed water heater, said float being adapted to actuate a valve 46 disposed in the cold water supply pipe 47. A single float valve is thereby utilized to maintain a predetermined water level in both the feed water heater and in the filling water reservoir. The water delivered to the feed water heater 42 is heated by exhaust steam delivered to the heater through a pipe 48 which receives the exhaust steam from the pumps 12 and 14 and from the engines in the power-house. The heater 42 is shown as an open heater equipped with pans or plates 49 by means of which the steam and water are mingled, but obviously other types of heaters may be employed in this connection, if preferred. A pipe 51 connected with the heater is adapted to supply water to the power boilers so that the heater 42 is utilized not only for preliminarily heating the filling water but also as a feed water heater for the power boilers thereby performing a double function and eliminating the usual power boiler feed water heater. The filling water in the reservoir 8 which has been preliminarily heated in the heater 42 is further heated by blow-off steam which is delivered beneath the surface of the water in the reservoir by a pipe 52 communicating through a short pipe 53 with the blow-off main 9. Obviously a portion of the steam which is being discharged through the pipe 9 will rise in the pipe 53 and be discharged into the reservoir 8 where it is mingled with the filling water, whereby this water is directly heated by the blow-off steam from the boiler without being contaminated by the mixture of foul blow-off water therewith. The surplus steam from the feed water heater 42 is also utilized for heating the feed water, said steam being conducted through a pipe 54 and a branch 55 to the pipe 52. A safety valve 56 is preferably provided in the pipe 54 above the pipe 55 to permit escape of excess pressure. The check valve 57 interposed in the pipe 55 prevents backflow of blow-off steam from the pipe 53 into the feed water heater.

For the purpose of maintaining the temperature of the filling water in the reservoir 8 I have connected the refilling main 15 with the feed water heater through a circulating pipe 58 so that a constant circulation of the

filling water will be maintained through the pump suction pipe 59, the refilling main 15, the circulating pipe 58, the feed water heater 42 and the pipe 43 connecting the feed water heater with the reservoir. A pipe 60 provided with suitable branches 62 opening into the filling water reservoir 8 is connected with the pipe 31 so that when the valve 34 is opened upon reduction of temperature in the washing water reservoir to admit live steam to the washing water, live steam is also simultaneously admitted to the filling water reservoir 8.

From the foregoing it will be observed that the filling water is preliminarily heated by exhaust steam from the power boilers in the feed water heater 42 from whence it is delivered to the filling water reservoir. The water is constantly circulated from the filling water reservoir through the feed water heater so that it is continuously being heated in this heater and returned to the reservoir. Blow-off steam is also utilized for further heating the water in the filling water reservoir and, likewise, the surplus steam rising from the feed water heater 42, this surplus steam and the blow-off steam being mingled with the filling water in the reservoir 8 by discharging the steam below the surface of the water. Additional provision is made for heating the refilling water by live steam which is admitted through the pipe 60 to the filling water whenever the valve 34 is opened.

To prevent the collapse of reservoirs 7 and 8 upon the formation of vacuums therein I have provided vacuum valves 59' and 61. The filling water reservoir is provided with the usual overflow pipe 62' equipped with a vent pipe 63 and both of the reservoirs are provided with suitable sludge valves 64 through which the boilers may be drained and cleaned when desired.

It is believed that my invention and many of its attendant advantages will be understood from the foregoing without further description.

It will be obvious, that my invention contemplates mixing blow-off steam and water with the water in the washing water reservoir to heat the same and, at the same time, saving a portion of the blow-off water, that part of the blow-off steam is conducted to the filling water reservoir for heating the refilling water, that exhaust steam from the power pumps and boilers is utilized for preliminarily heating the filling water and that the surplus steam is mingled with the filling water in the reservoir 8 and, that provision is also made for admitting live steam to both the washing water and refilling water reservoirs.

While I have shown and described one preferred and practical embodiment of my invention it will be manifest that the me-

chanical details of construction are capable of variation within wide limits without departing from the essence of the invention or sacrificing any of the material advantages thereof.

I claim:

1. In a boiler washing and filling system, the combination of a reservoir for washing water, a reservoir for filling water, a blow-off main for conveying blow-off steam and water from a boiler, connections between the blow-off main and the washing water reservoir and between said main and the filling water reservoir, and thermostatic means for automatically controlling the deliverance of the blow-off steam and water from said main to the washing water reservoir.

2. In a boiler washing and filling system, the combination of a reservoir for washing water, a reservoir for filling water, a blow-off main for conveying blow-off steam and water from a boiler, means for delivering a portion of the blow-off steam and water to the washing water reservoir, means for controlling the quantity of blow-off steam and water delivered to the washing water reservoir, and means for conducting blow-off steam to the refilling water reservoir.

3. In a boiler washing and filling system, the combination of a reservoir for washing water, a reservoir for filling water, a blow-off main communicating with a catch-basin or the like, means connected with the blow-off main for delivering a portion of the blow-off steam and water to the washing water reservoir, means dependent upon the temperature of the water in the washing water reservoir for automatically controlling the amount of blow-off steam and water delivered to the washing water reservoir, and means connected with the blow-off main for delivering blow-off steam to the filling water reservoir.

4. In a boiler washing and filling system, the combination of a tank comprising a washing water reservoir, and a filling water reservoir, a blow-off main, means for mingling a portion of the blow-off steam and water with the water in the washing water reservoir, a heater, connections between said heater and the filling water reservoir, a single means for maintaining a predetermined level of water in said heater and filling water reservoir, and a pipe connected with the blow-off main for delivering blow-off steam to the filling water reservoir whereby said filling water is further heated.

5. In a boiler washing and filling system, the combination of a filling water reservoir, a blow-off main for conveying blow-off steam and water from a boiler, a heater connected with said filling water reservoir whereby the filling water is primarily heated before being delivered to the filling water reservoir, a pipe for delivering blow-

off steam to said filling water reservoir for further heating the water therein, and connections whereby the surplus steam from said heater is delivered to said pipe for heating the water in the filling water reservoir.

6. In a boiler washing and filling system, the combination of a filling water reservoir, a heater mounted adjacent said reservoir with its bottom disposed below the top of said filling water reservoir, means for supplying water to said heater, means for delivering steam to said heater whereby the water is heated, a float valve for controlling the water supply to said heater whereby a predetermined water level is maintained in said heater, and a pipe connecting said heater and filling water reservoir through which the reservoir receives its water supply from the heater and whereby the water in the reservoir is maintained at the same level as the water in the heater.

7. In a boiler washing and filling system, the combination of a filling water reservoir, a heater, a pipe for conveying heated water from said heater to the filling water reservoir, a pipe for conveying heated water from said heater to power boilers, means for delivering blow-off steam to the water in the filling water reservoir, and means for maintaining a circulation of water through the filling water reservoir and feed water heater.

8. In a boiler washing and filling system, the combination of a reservoir for washing water, a reservoir for filling water, a feed connected with the filling water reservoir, means for delivering blow-off steam from a boiler and surplus steam from said heater to the water in the filling water reservoir, means for preventing blow-off steam from entering the heater, and means for delivering a portion of the blow-off steam and water to the water in the washing water reservoir.

9. In a boiler washing and filling system, the combination of a washing water reservoir, means for mingling blow-off steam and water with the water in the washing water reservoir, means for conveying blow-off steam to the filling water reservoir, and means for conducting water from the bottom of the washing water reservoir and returning it to a higher level whereby to maintain a uniform temperature of the water in the washing water reservoir.

10. In a boiler washing and filling system, the combination of a washing water

reservoir, a filling water reservoir, a blow-off main, connections whereby a portion of the blow-off steam and water from a boiler are mingled with the water in the washing water reservoir, connections whereby blow-off steam is delivered to the water in the filling water reservoir, a heater connected with said filling water reservoir, means for circulating water from the filling water reservoir through the heater, and means for maintaining a circulation of the water in the washing water reservoir.

11. In a boiler washing and filling system, the combination of a washing water reservoir, a blow-off main, connections whereby blow-off steam and water may be mingled with the water in the washing water reservoir, thermostatic means for controlling the amount of blow-off water and steam delivered to said washing water reservoir, connections for delivering blow-off steam to the water in the filling water reservoir, a heater connected with the filling water reservoir, a pipe for delivering exhaust steam to said heater, connections whereby the surplus steam from the heater is delivered to the filling water reservoir, means for maintaining a circulation of water in the washing water reservoir, means for maintaining a circulation of water through the filling water reservoir and heater, a washout main connected with the washing water reservoir, and a refilling main connected with the filling water reservoir.

12. In a boiler washing and filling system, the combination of a washing water reservoir, a refilling water reservoir, a blow off main, means for delivering blow off steam and water from said main to the washing water reservoir, means for delivering blow off steam to the refilling water reservoir, a heater mounted adjacent to said refilling water reservoir, means for supplying water thereto, a pipe connecting said heater and said refilling water reservoir, a single float valve for controlling the supply of water to said heater whereby a common and uniform water level is maintained in said heater and in said refilling water reservoir, means for supplying steam to said heater to heat the water therein, and means for conducting the surplus steam from said heater to said refilling water reservoir.

FRANK W. MILLER.
